ABSTRACT: A gas pump of a liquid-ring type whose housing structure has a first suction opening and a pressure opening at the respective localities where the liquid ring, formed by centrifugal force during operation of the pump rotor, penetrates most deeply and least deeply into the intervane spaces of the rotor and is additionally provided with at least one further suction opening which is located between the first suction opening and the pressure opening. The additional suction opening, relative to the direction of rotor rotation, has its leading end spaced from the lagging end of the first suction opening an amount equal to, or larger than, the vane division of the rotor. A suction duct is connected to the additional suction opening which is separate from the suction duct that communicates through the first suction opening with the interior of the pump housing.

PATENTED APR 20 1971

3,575,532

GAS PUMP OF A LIQUID-RING TYPE

The invention relates to a gas pump of a liquid-ring type and preferably to pumps for evacuation purposes.

Pumps of this type comprise, for example, an approximately cylindrical housing partially filled with liquid such as water, in which a vane rotor is eccentrically journaled, the housing being covered on both axial sides of the rotor by control plates of which each is provided with suction and pressure openings for the medium to be pumped, these two openings in each control plate being arcuately spaced from each other. The rotation of the rotor causes the liquid, hereinafter referred to as water although other liquids are also applicable, to be flung outwardly and thus form along the inner periphery of the housing a water ring which rotates with the rotor and which is guided on a raceway space formed by the housing conjointly with the appertaining two control discs of the housing structure. The rotating ring of water conjointly with the vanes of the rotor forms respective cells which during rotation of the rotor periodically enlarge and thereafter reduce in volume.

The housing structure, or more specifically the above-mentioned control discs, have suction openings in the form of arcuately elongated slots at those localities where the cells commence to enlarge their volume, that is, where the ring of water reduces its depth of penetration into the intervane spaces of the rotor. The gas to be delivered or evacuated is inducted into the cells through these suction openings. During the continued rotation of the eccentrically journaled rotor, the water again penetrates more deeply into the intervane spaces thus reducing the cell volume with the result of compressing the gas enclosed in each cell. The pressure openings, also preferably designed as arcuately elongated slots, are spaced from the suction slots by an angle of approximately 180°. When each cell during rotary travel reaches its point of highest compression, it communicates with a pressure opening so that the compressed gas is ejected.

Gas or vacuum pumps of the type described are generally known and available in the trade. Reference may be had, for example, to German Pat. No. 269,531 (single-acting pump) or to U.S. Pat. No. 1,718,294 (double-acting pump).

In practice, vacuum pumps of the type described above are employed for single-stage action in pressure-ratio ranges of about 1.5 (for example 500 Torr to 760 Torr) to about 25 (for example 30 Torr to 760 Torr). When the pressure ratio is low, the pump discharging pressure (for example 760 Torr) is attained relatively early; hence the pressure slot should likewise commence at an earlier point of the rotational rotor travel and consequently, as seen in the peripheral direction, should be given a longer arcuate extent. Analogously, for a larger pressure ratio, the pressure slot should have a considerably shorter extent. For economic reasons the sickle-shaped pressure opening is normally constructed for a relatively large pressure ratio and hence is made relatively small. In order to prevent excessive compression and turbulence losses when operating at a lower pressure ratio, that is, at a higher suction pressure, the housing structure is provided with a few bores located slightly ahead of the sickle-shaped pressure openings, likewise seen in the direction of rotation. Those bores that are located in the region of the discharging pressure, readily permit the gas to pass through, whereas the water located on the backside of the control disc covers all other bores located in the region of lower pressure.

The valve action is even more effective if the above-mentioned bores are provided with ball valves whose balls open or close in dependence upon the pressure ratio.

The described pumping cycle in each case is predicated upon the presence of a liquid ring which more or less enters into the intervane spaces of a rotating pump rotor, as well as upon at least one suction opening and a pressure opening arranged at the respective localities where the water ring has substantially the shallowest and deepest penetration into the intervane spaces. All gas pumps of the liquid-ring type are predicated upon this fundamental principle of design and operation, including all of the known modifications of this type of pump.

It is an object of the invention to improve liquid-ring pumps for gas pumping purposes with the aid of relatively slight structural changes and additions, in such a manner as to improve the efficiency of the pump and enlarge the available possibilities of use.

Another object, conjoint with the one just mentioned, is to devise a gas pump of the liquid-ring type which is capable of performing the function of two pumps for respectively different suction pressures.

Another object of the invention is to provide a pump applicable for mixing and conveying gases and/or vapors for the purpose of performing chemical reactions within.

It is still another object of the invention to provide a gas pump in which the occurrence of cavitation is avoided.

To achieve these objects, and in accordance with a feature of the invention, a pump generally of the liquid-ring type is provided with at least one additional suction opening located between the normally employed suction opening and the pressure opening. Seen in the running direction of the pump

rotor, the additional suction opening is spaced from the end of the first-mentioned suction opening by an arcuate amount at least equal to the vane division of the rotor, and a separate suction duct or conduit is provided to communicate through the additional suction opening with the interior of the housing structure.

The invention will be further described with reference to an embodiment illustrated by way of example and partly in section on the single illustration presented on the accompanying drawing.

Shown on the drawing is a gas pump of the liquid-ring type designated by 1, the illustration of the pump being schematic and with the circular control disc facing the observer and forming part of the housing structure removed to expose the interior. The housing structure further comprises an approximately cylindrical housing portion 3 which at both axial ends is enclosed by the control discs of which only the rear disc 16 is visible. A rotor 2 carrying a number of uniformly distributed vanes around its peripheral surface is eccentrically journaled in the housing and, during operation of the pump, rotates in the clockwise direction indicated by an arrow 17.

The gas to be delivered is confined in a vessel 10 which is connected with the suction duct 8 of the liquid-ring pump 1.

The duct 8 communicates through a suction opening 5 in the control disc 16 with the interior of the working space of the pump. The suction opening 5 is arcuately elongated to the shape of a crescent or sickle, or rather, to only one-half portion of such a shape. Through the suction opening 5, the

gaseous medium is inducted into the pump space where it enters into a cell formed between each two adjacent rotor vanes and the rotating, eccentric ring of liquid. As described above, the gas enclosed in each cell is compressed during the clockwise rotation of the rotor until it is ejected in compressed condition through the pressure opening 4 of the control disc 16. For vacuum producing purposes the compression of the gas is up to the atmospheric pressure obtaining at the pressure duct or conduit 9 of the pump.

According to the invention, the pump is further provided

with an additional suction opening 6 in the control disc 16 which forms part of the housing structure. Another suction duct 7 communicates through the additional suction opening 6 with the working space of the pump. The suction opening 6, relative to the direction of rotor rotation, is spaced from the

end of the first suction opening 5 by an arcuate distance corresponding at least to one vane division t so that the two suction openings 5 and 6 are always separated from each other by at least one rotor vane. The additional suction opening 6 extends, relative to the rotational direction, approximately

into the region where the water ring 19 again enters into the vane interspace of the rotor up to the region of commencing compression. The rotor cells passing by the suction opening 6, if no gas were inducted through the suction opening 6, would have approximately the same gas pressure as obtains at the suction duct 8.

The gas quantity Q_2 inductable through the additional suction opening 6 can be determined by the following formula:

$$Q_2 = Q_1 \left(1 - \frac{p_1 \cdot \varphi_1}{p_2 \cdot \varphi_2} \right)$$

in which Q_1 denotes the inducted quantity of gas, p_1 the suction (induction) pressure, $\varphi_1 = p_1 - p$ denotes the pressure difference between induction pressure and vapor partial pressure in the region of the suction opening 5; and Q_2 , p_2 , φ_2 denote the corresponding physical data in the region of the additional suction opening 6. The additional gas quantity Q_2 can be inducted through the suction conduit 7 under the suction (induction) pressure p_2 .

For operation at high pressure ratios it may be preferable to have the end of the additional suction opening 6 located in the region of compression.

If required, one or more precompressors, for example an ejector as shown at 11, may be connected to the additional suction duct 7 ahead of the additional suction opening 6, the precompressing ejectors or the like devices being operated with gas and/or steam. When providing such an ejector, the driving medium 20 entering through a control valve 14 is accelerated in a driving nozzle 12 and when entering into the suction space, vigorously entrains the medium to be delivered. The diffusor 13 which follows the ejector nozzle 12 compresses the mixture of delivering medium and the driving jet (air or steam) up to the desired induction pressure.

By connecting the suction space of the ejector with the first suction duct 8 or the space 10 to be evacuated, an increase in inducted quantity Q_1 at the suction pressure p_1 can be attained. This will be elucidated by a numerical example:

Assume that a pressure of 30 Torr obtains in the suction duct 8. The mixture of driving jet and delivering medium in the ejector 11 can then be condensed, for example, to 120 Torr. Since this pressure is considerably higher than that obtaining at the suction duct 8 of the pump, this mixture readily flows through the suction opening 6 into the interior of the rotor cells located in the region of this additional suction opening 6 at a pressure of 30 Torr, whereafter it is condensed to 120 Torr. Thereafter the two gas quantities Q_1 and Q_2 which enter into the vane cells through the suction ducts 8 and 7 are conjointly ejected through the pressure opening 4 into the pressure duct 9 of the pump.

By means of the throttle valve 18 in the additional suction duct 7, the gas quantity additionally supplied to the pump through the suction opening 6 can be controlled. This can be done, for example, in such a manner that the same gas quantity always passes through the pressure opening 4 independently of the pressure obtaining at the suction duct 8.

With any of the above-described arrangements according to the invention there results an overall improvement in efficiency of the pump. This is because the power demand of the pump is largely determined by the water-ring friction, gap losses and other losses. Since these remain to a large extent constant with the invention, it remains only to raise the compressing work for the additional gas entering through the suction duct 7 or for the mixture of driving and delivering gas entering through the same duct.

By connecting to the additional suction opening a further apparatus which is to be evacuated at a somewhat higher suction pressure, for example suction rollers for the paper industry, rotating filters or the like equipment, then the usually required two different pumps are substituted by a single pump operating with a considerably better overall efficiency since the hydraulic losses (liquid-ring friction, slot and gap losses) are not appreciably increased additionally. In totality, therefore, a reduced overall amount of machinery is afforded, also an improved efficiency as well as the avoidance of cavitation.

A further enlargement in the field of use of such a pump results if a gas or steam ejector is connected ahead of the additional suction opening. According to another feature of the invention it is also of advantage to connect the suction

space of such an ejector and the first-mentioned suction opening with one and the same space or vessel to be evacuated. This also results, in totality, in increasing the inducted quantity of gas and consequently the efficiency of the pump.

A pump according to the invention is advantageously applicable for mixing and conveying gases and/or vapors for the purpose of performing chemical reactions within a space sealed with the aid of the liquid-ring pump. This is achieved as described above by supplying the two gaseous or vaporous reactants through the two suction openings respectively into the pump.

Another significant advantage of the additional suction opening in a pump according to the invention resides in the fact that this opening permits inducting into the pump such a quantity of fluid and compressible medium, for example gas, that even if the pressure ratio varies greatly between the first suction opening and the pressure opening, the quantity of gas delivered through the pressure opening remains constant so that the pressure opening can be given a uniform and constant outlet cross section. In this case valves of any kind are no longer required. If desired in this case, the required quantity of air may be supplied from an enclosed space, such as a vessel, that is likewise to be evacuated, and this supply can be controlled by a manually actuated or pressure-responsive throttle valve. It is further possible to connect the additional suction opening through such a throttle valve directly with the ambient air or with the pressure space of the pump.

As already indicated, the invention is not limited to the illustrated and described embodiment but can be analogously applied to any other design of gas pumps according to the liquid-ring type. This includes designs in which two or more working regions are provided along the housing periphery of which each region comprises its own suction slot and pressure slot. Such twin pumps are known, for example, from the above-mentioned U.S. Pat. No. 1,718,294 and U.S. Pat. No. 1,797,980.

The invention is further applicable in the manner described above, to pump designs in which the suction and pressure slots are not located in the lateral control discs but are located in control cylinders or control cones which laterally protrude into the rotor. The particular embodiment shown for illustration and description in the present specification comprises two rotor half-portions, each having one of the two control discs coordinated thereto. However, the two half-portions of the rotor can also be separated from each other by a partition located in the middle of the rotor and in the middle of the cylindrical housing, so that, by applying the invention, there will result a total of four suction openings for four different suction pressures.

The invention also contemplates within its scope the provision of more than one additional suction opening between the conventional suction opening and pressure opening. In this case, each of the additional openings, seen in the rotational direction of the rotor, is to communicate with a cell space having a pressure higher than that obtaining at the next-preceding additional suction opening.

As further shown on the drawing, another space or vessel 15 to be evacuated having a somewhat higher pressure than the space or vessel 10 can be connected to the suction duct 7. This is preferably done so that the connection of vessel 15 can be effected in lieu of the ejector 11 or in addition thereto. For this purpose, the illustrated embodiment shows a shutoff valve 14 which in conjunction with the valve 18 affords the just-mentioned selective operation, although if desired another shutoff valve may be provided in the branch conduit which extends from vessel 10 to suction conduit 7 and contains the ejector 11.

In conclusion, it is of interest that cavitation in the above-described pump according to the invention can be avoided. This is achieved by inducting additional air into the pump so that the vapor contained in the rotor cells is prevented from condensing.

Upon a study of this disclosure it will be apparent to those skilled in the art that the invention permits of various modifications other than those particularly illustrated and described herein, without departing from the essential features of the invention and within the scope of the claims annexed hereto.

We claim:

1. A gas pump of the liquid-ring type for pumping a medium, comprising a rotor having impeller vanes uniformly distributed over its periphery, a housing structure containing the rotor and forming around said rotor an annular racing space for a centrifugally formed ring of liquid having respective arcuately spaced localities where the liquid ring during pump operation enters the most and the least respectively into the intervane spaces of said rotor, said housing structure having a first suction opening and a pressure opening at said localities and having respective suction and pressure duct means communicating with said space through said two openings, said housing structure having at least one additional suction opening located between said first suction opening and said pressure opening, said additional suction opening having its leading end, relative to the direction of rotor rotation, spaced from the lagging end of said first suction opening an arcuate amount at least equal to a vane division of said rotor, and another suction duct communicating with said space through said additional suction opening, said medium drawn through said first and additional suction openings and

leaving said pump through said pressure opening.

2. In a gas pump according to claim 1, said additional suction opening extending to the region where said liquid ring reenters into said intervane spaces of said rotor.

3. A gas pump according to claim 2, comprising control means connected to said pump for supplying gas to said additional suction opening in sufficient quantity to ensure that the quantity of gas at said pressure opening remains substantially constant and independent of changes in induction pressure at said first suction opening.

4. A gas pump according to claim 1, comprising control means connected into said other suction duct for controlling the amount of fluid passing through said duct.

5. In a gas pump according to claim 4, said control means being a throttle valve which can be manually adjusted to control the flow of gas through said other suction duct.

6. In a gas pump according to claim 4, said control means being a throttle valve which operates in response to pressure to control the flow of gas through said other suction duct.

7. A gas pump according to claim 1, comprising a precompressor connected to said other suction duct, said precompressor being operable with a fluid for evacuating a chamber evacuated via said suction duct means.

8. In a gas pump according to claim 7, said precompressor being an ejector, said ejector having a suction space connected with said suction duct means.
